DESIGN FOR OPENWORK BEAD FABRIC OR SIMILAR ARTICLE

Max Tannenbaum, New York, N. Y.

Application November 19, 1937, Serial No. 73,030

Term of patent 3½ years

To all whom it may concern:

Be it known that I, Max Tannenbaum, a citizen of the United States and resident of New York, in the county and State of New York, have invented a new, original, and ornamental Design for Openwork Bead Fabric or Similar Article, of which the following is a specification, reference being had to the accompanying drawing, forming part thereof.

In the drawing:

Fig. 1 is a plan view of an openwork bead fabric or similar article for ladies' hand bags or the like, showing my new design.

Fig. 2 is an enlarged fragmentary sectional view on line 2—2 of Fig. 1.

The characteristic feature of my design resides in the color contrasts, the dark colors defining a six pointed figure.

I claim:

The ornamental design for openwork bead fabric or similar article substantially as shown and described.

MAX TANNENBAUM.
